UNITED STATES PATENT OFFICE

GEORGE H. ANGERT, OF CINCINNATI, OHIO, ASSIGNOR TO ANGERT BROTHERS, A PARTNERSHIP COMPOSED OF ARTHUR C. ANGERT AND GEORGE H. ANGERT, OF CINCINNATI, OHIO

ADJUSTABLE TABLE

Application filed August 31, 1923. Serial No. 660,311.

My invention relates to tables, and to articles of furniture to have tops convertible from one size to another.

The specific object of my invention is to provide a table, usually a kitchen table which is convertible from normal size porcelain top table, to a double size wooden table, without removal or addition of parts. I have found that by a simple geometrical calculation, I can provide a table which is in two sections hinged at the middle, and adapted to fold on each other, the one section being pivoted to the table so that it will rotate around from position to cover the entire frame, to position at right angles, to cover half of the frame. Then on the lower face of the hinged half, so arranged as to be exposed when folded over the pivoted half, I mount a porcelain cover.

I accomplish my object by that certain arrangement of parts to be hereinafter more specifically pointed out and claimed.

In the drawings:

Figure 1 is a plan view illustrating the table and the means for calculating the pivotal position of the one section of the top.

Figure 2 is an end elevation of the table when converted into a porcelain top.

Figure 3 is a perspective of the table when used with the porcelain top.

Figure 4 is a perspective showing the partial operation of unfolding the top.

Figure 5 is a perspective view of the table showing the top in its double area, and located in position.

In proceeding to make up my table, I first determine upon the size desired for the porcelain top, and for the double area when unfolded, which will be twice the area of the porcelain top. I then lay out on a drawing,

the size of the porcelain top as illustrated in w, x, y, z (Figure 1). I then take the median line of the said view and at right angles thereto, I draw in a figure which represents the top turned at a right angle. This is shown in the

figure a, b, c, d . I may then finish out the area of the double top by drawing in the folding half as shown at c, d, e, f . From point c I draw an arc, and from the nearest corner w I draw an arc of equal radius. With the two intersections of these arcs as points I

draw a line m . I then draw an arc from point a , and an arc from point x of equal radius, and from the two intersections of these arcs, I draw a straight line n . Where lines n and m intersect at the point p on the table frame is the pivot point for the pivoted portion of the table top. The other portion of the top is then made of equal size thereto and hinged to its long edge. 55

When so constructed it is evident that upon 60 swinging the rectangle w, x, y, z , around to position a, b, c, d , the line w, z , will lie along the middle of the space formerly occupied by the rectangle w, x, y, z .

Referring now to the table itself, I have 65 indicated legs 1, frame boards 2, and a cross board 3 for the pivot of the one section. The one half section that is pivoted is marked as 4, and the pivot may be formed of a screw bolt 4^a set through the board 3, and screwed 70 into the base of the table section 4. The pivot point will be located as described by the layout of Figure 1 and the frame built accordingly.

The section 5 of the table is hinged to the 75 section 4 along one of its long edges, by means of hinges 6. As this section is to be on top when the table is folded up, I finish the bottom of the section 5 with the desired finish. While I have termed the top a porcelain top, 80 I do not wish to be understood as limiting myself to any particular kind of finish, but only as bringing out the fact that a special finish can be provided which is different from the rest of the table, without detracting from 85 the appearance of the table when unfolded, since this finish can be placed on what is the underside of the folding section.

In Figure 3 the table is shown folded up. In Figure 4 the operator has started to fold 90 up the section 5 and to swing the section 4 on its pivot. In Figure 5 the swinging has been completed, and the double top is open and down on the frame.

In forming a porcelain finish, I find it convenient to obtain the porcelain in the shape of a plate having a flange 5^a, which is screwed as at 5^b to a wooden filler 5^c. The filler will be in the form of a matching top to the section 4, to give a neat job. 95 100

It is evident that my invention is specially advantageous in a kitchen where a porcelain top is often desirable, and the expense of a large top makes it within range of all users to have one of my tables for working on the porcelain top, and still unfold it to larger size where needed as a service table or a table from which to eat.

Having thus described my invention, what I claim as new and desire to secure by Letters Patent, is:—

1. In a table the combination with a frame of a table top section adapted in one position to cover the frame, and having a pivot to said frame, said pivot being so located that the said top section can swing to a position at right angles to its first noted position in which case it will cover but one half of the frame, and a second top section of equal size to that first mentioned and hinged thereto along one side, said hinge being arranged so that when in the second position of the first section above described the second section will fold to a position to cover the remaining half of the table, and when folded up, said second section will lie over and cover the first noted section, said second section having a porcelain cover thereon comprising a flanged metal plate set over the bottom of the second section, with the flanges embracing the edges of said section and secured thereto, the porcelain finish of which will be uppermost when folded over the top of the first section noted, the opposite side of the second section being of the same finish as the top of the first section.

2. In a table, a leg supported frame, a first top section pivotally connected to said frame for swinging movement in a horizontal plane, to permit said section to be moved from a position covering the frame to a position covering substantially only half of the frame, a second top section equal in size to the first section, and having one of its side edges hinged to one side edge of the first top section to permit the second section to be superposed on the first section to form a kitchen table, or to lie along side the first section to form a dining table, and a porcelain finished unobstructed metal cover on one side of the second section, and adapted to form the upper surface of the table top when the second section is superposed on the first section, the opposite side of the second section being of the same nature and finish as the upper surface of the first section, the metal cover adding sufficient weight to the second top section to hold both sections in either of their positions.

GEORGE H. ANGERT.
